UNITED STATES PATENT OFFICE.

ALBERT PATITZ, OF WEST MERIDEN, CONNECTICUT, ASSIGNOR TO BRADLEY & HUBBARD MANUFACTURING COMPANY, OF SAME PLACE.

DESIGN FOR INKSTAND-HOLDERS.

Specification forming part of Design No. **11,406**, dated September 9, 1879; application filed December 2, 1878.
[Term of patent 3½ years.]

To all whom it may concern:

Be it known that I, ALBERT PATITZ, of West Meriden, in the county of New Haven and State of Connecticut, have invented a new Design for Inkstand-Holders; and I do hereby declare the following, when taken in connection with the accompanying photographic illustration, to be a full, clear, and exact description of the same, and which said illustration constitutes part of this specification, and represents a perspective view.

This invention relates to a design for holder for inkstands, such as consist of a platform on which the inkstands rest, and a rack for the support of pens; and consists in the configuration as hereinafter described, and shown in the accompanying illustration.

The base or platform is of elliptical shape, its front and rear sides reversed curves, meeting in a point at each end. The edge is inclined, and ornamented by representation of the tongue and dart molding. The ornamentation may, however, be changed, the peculiar shape

constituting the characteristic of this part of the design.

The pen-rack consists of a frame composed of an upright projecting at each side in curved lines, forming hooks on which to rest the pen-holder, the two sides connected together by a semicircle at the top, the space between filled with scroll-work, and the tip also crowned with scroll-work, as shown in the accompanying illustration.

I claim—

The design for inkstand-holder, consisting of the pen-rack, its two sides forming a succession of curves contracting toward the top, with the supporting-hooks projecting therefrom, the two sides united at the top by a semicircle, the intermediate space filled with scroll-work, and the rack tipped with scroll-work, as shown in the accompanying illustration.
